KEY OPERATED TRANSMITTER

Carl W. Swan, Skokie, Ill., assignor to Teletype Corporation, Chicago, Ill., a corporation of Delaware

Application August 6, 1943, Serial No. 497,591

2 Claims. (Cl. 177—380)

1

This invention relates to apparatus for the transmission of permutation code signals and more particularly to transmission apparatus in which predetermined permutation code signals only are transmitted.

Certain signals of a permutation system are sometimes assigned to special supervisory control purposes. Under such circumstances a special limited keyboard becomes convenient which accommodates these code signals only, but as the particular code combination may vary according to custom or necessity it is desirable that the limited number of keys may be altered through the entire range of the permutation code.

The object of the present invention is to provide apparatus for the transmission of certain code signals only wherein such signals are optionally predetermined according to permutation.

A further object of the invention is to provide means whereby an operator of the apparatus may, by a visible indication, be notified of the transmitted code signal.

The apparatus, in general, consists of a set of keys, each one upon being depressed, operates a bail to permutably actuate code bars. An extension on each bail establishes two electrical circuits, one of which lights a signal lamp to indicate the key that has been depressed. The second circuit energizes an electromagnet which through an armature releases a cam distributor for a cycle of operation, whereby the predetermined code signal is transmitted over an associated signaling channel.

A more detailed understanding of the invention may be had from the following description with reference to the accompanying drawings in which:

Fig. 1 is a front elevational view of transmitting apparatus embodying the present invention;

Fig. 2 is a side elevational view of the apparatus shown in Fig. 1;

Fig. 3 is a side sectional view, partly broken away, taken approximately on line 3—3 of Fig. 1;

Fig. 4 is a side sectional view, taken approximately on line 4—4 of Fig. 1, showing in detail a timing device utilized in the present invention;

Fig. 5 is a plan sectional view taken approximately on the line 5—5 of Fig. 1;

Fig. 6 is a detail sectional view taken approximately on the line 6—6 of Fig. 5; and

Fig. 7 is a schematic wiring diagram showing the electrical circuit of the apparatus.

The apparatus is mounted on a vertical base 11 which, in turn, can be mounted securely by

2

any suitable means (not shown) in its desired operating position. A bracket 12 is mounted securely to the base 11, on the left side, by means of screws 13. Mounted securely to the bracket 12, in a vertical position, is a rod 14 which is held in place thereon by means of screws 16. Mounted pivotally upon the rod 14 are three key levers 17, 18, and 19, upon which are secured key tops A, B, and C, respectively. The key levers 17, 18, and 19 extend toward the right and terminate in ends 21, 22, and 23, respectively. These levers extend through an opening in a bracket 24 which is secured to and at right angles to the base 11.

Adjacent the lever ends 21, 22, and 23, are three vertically positioned levers 26, 27, and 28, which are so placed as to be engaged by the lever ends 21, 22, and 23 upon the depression of any of the key tops A, B, or C. The levers 26, 27, and 28 are integral parts of code bails 29, 31, and 32, respectively, which are pivoted in a block 33 which is fastened securely perpendicularly to the bracket 24. The code bails 29, 31, and 32 each have a series of five code lugs 34 thereon, each lug corresponding to an impulse of a five-unit permutation code signal. The code lugs 34 are reversible and may be positioned with their projection portions either above or below the code bails. The code bails 29, 31, and 32 each have an arm 36, 37 and 38, respectively, as shown in Figs. 2, 3, and 4.

Pivoted within slots in the block 33 are five code levers 39, which are held normally in an outward position by means of individual springs 41 which are connected to a rearwardly extending lug at the bottom of each of the code levers. The code levers 39 are held in their correct lateral position by means of guide plates 42 (Figs. 2 and 3), pairs of which are positioned one on each side of the code levers. The front edge of the code levers are formed with lugs and slots. A code lug 34 may engage the lugs, or enter into the slots, upon the forward movement of a code bail, depending on the position of the projection portions of the lug with respect to the bail.

The top edge of the code levers are formed with an upwardly-extending arm at its end, as designated by the numeral 43. The rearward portion of the top edge of the code levers is formed with two lugs having a slot separating them. This is so designed that a locking bar 44 may enter within the slot between the two lugs or may be positioned in front of the forward lug, and which acts to lock the code levers either in their normal position or in an inward position, depending on the signal which is to be transmitted.

Referring now to Fig. 5, a shaft 46 is journalled within bearing brackets 12 and 47 which are secured to the base 11. The shaft 46 is composed of two cam assemblies, one each toward its right and left ends, and which are separated by a section of integral shafting. Surrounding the middle section of the shaft 46 is a hollow sleeve 51 which is free to rotate independently of any movement of the shaft. Positioned securely at one end of the sleeve 51 is a gear 52 which engages a pinion 53 (Fig. 4) fast to a shaft of a motor 54. The sleeve 51 is continuously rotated through the engagement of its gear 52 with the pinion 53 of the motor 54. The shaft 46, however, does not rotate continuously.

A cam assembly which has been designated generally by the numeral 48 has five cams 56 to 60 inclusive and a disk 61, thereon. Five cam followers 64 to 68, inclusive, are pivotally mounted in slots in a block 63 which is secured to the base 11, and are normally held in a position against the cams 56 to 60, by means of springs 70, one individual to each cam follower.

The cam follower 64 is in engagement with the cam 56, Fig. 2, and its forward end is connected to the locking bar 44, previously mentioned. As the locking bar 44 is made of sufficient width to engage all five of the code levers 39, it is necessary to have an actuating member at each of its ends. Therefore, the end opposite from that formed by the cam follower 64 is formed by the cam follower 68, which is engaged by the cam 60. Thus, upon rotation of the shaft 46 the cam followers 64 and 68 will be rocked counterclockwise, Fig. 2, due to the contour of the cams 56 and 60, during a predetermined portion of the cycle of operation of the shaft 46. This, in turn, will cause the locking bar 44 to move into the notch or in front of the lug on the code levers 39, thus locking the code levers in either their forward or rearward positions.

Another cam follower 65 is positioned so as to be engaged by a cam 57 and is formed with a member 71 extending upwardly and to the rear of the cam and the cam shaft, and a forwardly extending member 72 in front of the cam and the cam shaft. The member 71 serves to engage and release a clutch element, the operation of which will be hereinafter explained. The member 72 acts to lock an armature 73, the operation of which will also be thoroughly explained later.

The cam followers 66 and 67 are each formed with a forwardly-extending arm, in the shape of a hook, which is used to lock the bail 32 and the bail 31, respectively, in its forward position. This locking operation extends through a portion of the cycle of operation of the shaft 46, depending on the contour of the associated cams 58 and 59. The disk 61 has a notch in its periphery which is engaged by a roller 74 (Fig. 3) at the end of the cycle of operation of the shaft 46, and which is secured at the end of a pivoted rod 76, and normally held against the surface of the disk by means of a spring 77. Upon the rotation of the shaft 46 to a position whereat the roller 74 can engage the notch in the disk 61, which it will be forced to do by the action of the spring 77 pivoting the rod 76 toward the disk, the clutching mechanism will be completely released, as explained later, to serve as an anti-singing device. Thus, the roller 74 detents the disk 61 and its connected clutching mechanism, with respect to the member 71, so as to positively disengage the clutch teeth and prevent any rasping due to in-

complete disengagement from the continuously rotating sleeve 51.

A bracket 78 (Fig. 2) secured near the top of the base 11, is a supporting member for an electro-magnet 79. The magnet 79 is adjacent the upper portion of the armature 73, the armature being normally held away from the magnet by means of a spring 81. In a normal position, as previously mentioned, the armature is held from the magnet 79 and is positioned on the forward upturned end 72 of the cam follower 65. Upon energization of the magnet 79 the armature 73 will be drawn toward the magnet, its lower end being moved free from the upturned end 72 of the follower 65. When this occurs the corresponding spring 70 pivots the cam follower 65 in a clockwise direction as viewed in Fig. 3, which results in the member 71 likewise moving in a clockwise direction and releasing the clutch mechanism, thus allowing the shaft 46 to be engaged for rotation.

The locking bar 44 is formed with a pivoted downwardly-extending lever 82 having a hook at its end (Fig. 2), which, under certain conditions, engages an associated hook which is formed on an upwardly-extending lever 83 which is pivotally mounted in a slot in the block 33. When the hooks engage each other a non-repeat condition exists in the transmitting apparatus, as will be explained fully in conjunction with the operation of the apparatus.

Positioned adjacent the block 33 and below the levers 36, 31, and 38 (of the code bails 29, 31, 32, respectively), are three double contact electrical switches 84, 86, and 87 (Figs. 2, 3, and 4). These switches are normally open, no electrical circuit being established as a result. The levers 36, 37, and 38 are positioned immediately above the electrical switches so that if one of the three bails is pivoted in a clockwise direction (Figs. 2, 3, and 4) the lever will be forced downwardly to engage the top insulated portion of the electrical switch and cause it to move downwardly, thus closing the two contacts and establishing two electrical circuits. The closing of one of the contacts establishes a circuit which energizes the magnet 79, which, in turn, causes the armature 73 to be drawn toward the magnet thus allowing the cam follower 65 to pivot in a clockwise direction, as viewed in Fig. 3, and also allows the member 71 to move in a clockwise direction, thus releasing the shaft 46 to rotation by the engagement of the clutching mechanism with the sleeve 51. The closing of the second electrical contact in the switch establishes a circuit in which is connected an electric light corresponding to the bail which has been moved in the clockwise direction. The establishment of this circuit causes one of three electric lights 88, 89, or 90 to be illuminated, indicating to the operator which of the three key tops A, B, or C has been depressed.

Positioned just behind the upwardly-extending arm 43 of the code levers 39 are six electrical switches 92 to 97, inclusive. The electrical switch 92 is normally in a closed position, whereas the electrical switches 93 to 97, inclusive, are normally open. The latter switches 93 to 97, inclusive, are aligned with the upwardly-extending arms 43 of the code levers 39, one electrical switch being behind each of the five code levers. Upon a clockwise movement (Fig. 2) of any of the code levers, by engagement with the corresponding code lugs on the code bail, the upwardly-extending arm 43 will be moved inwardly, thus engaging its associated electrical switch and clos-

ing it. These switches, in turn, correspond to the five impulses in a code signal, such as the Baudot five-unit code. The switch 92, which is normally closed, is opened during a certain part of the cycle of operation of shaft 46, by means of a lug 98 (Fig. 2) which forms an end of the locking bar 44. At the same time that the locking bar 44 moves downward to lock the code levers 39 in their forward or rearward positions the lug 98 thereon will cause the electrical switch 92 to be opened, thus breaking a previously-established circuit. Such a circuit interruption is necessary in order to deenergize the magnet 79 which has previously been energized by the closing of one of the electrical switches 84, 86, or 87 upon the depression of its corresponding key top. This conditions the magnet 79 so that it will be in readiness to reinitiate a cycle of operation of the shaft 46 when one of the key tops A, B, or C is again depressed, providing that the switch 92 has been opened, thus allowing the armature to have returned to its normal position.

Fastened securely to the sleeve 51 so as to rotate therewith is a ratchet wheel 101 (Fig. 5) which is located at the opposite end of the sleeve from the previously mentioned gear 52. Connected to the disk 61, by means of a post 102 (Fig. 6) are three pawls 103. Each of these pawls has a tooth 104 thereon, which are in staggered relation to each other. These teeth are positioned in such a manner so that upon engagement of the clutching mechanism, later to be explained, one of the three teeth will immediately engage the teeth on the ratchet wheel 101, as the teeth are together staggered a distance equal to the distance between adjacent teeth on the ratchet wheel. The pawls 103 each have individual springs 105 urging them in a counterclockwise direction, as viewed in Fig. 6. When a tooth on one of the pawls engages the ratchet wheel power is transmitted from the constantly rotating sleeve 51 to the shaft 46. The pawls and springs rotate with the shaft 46, as they are connected to the disk 61 which is fastened securely to the shaft 46. The ends of the pawls are under the control of the member 71, previously mentioned, which, when in its downward position, engages the pawls and causes them to move in a clockwise direction (Fig. 6), thus releasing the tooth of the pawl from the ratchet wheel and disconnecting the drive to the shaft 46. A post 108, secured to the disk 61, limits the clockwise movement of the pawls 103. Upon the armature 73 being moved, due to the energization of the magnet 78, the cam follower 65 moves upward, as already explained, with the result that the member 71 likewise moves upward and releases the ends of the pawls 103. The springs 105 cause the pawls to be urged toward the ratchet wheel, the tooth of one of the pawls engaging therewith, and thus again causing the shaft 46 to rotate through a cycle of operation.

A timing device is disclosed in Fig. 4 which permits the visible signal, which is given when any one of the three key tops has been depressed, to remain operative for a predetermined length of time. This timing device is associated with one key only, key top A being designated as the associated key in the present disclosure. Surrounding a narrow section of the sleeve 51, on an inner surface, is an eccentric 106 about which is positioned a pawl 107. The pawl 107, which is free to rotate in an eccentric manner with respect to the constantly rotating sleeve 51, is positioned by means of a spring 108 so as to be in

engagement with a ratchet wheel 109 which is secured to the bracket 24 (Fig. 1). A second pawl 111 is pivotally secured by means of a rod 112 which extends from the lower portion of the code bail 29 in such a manner that the spring 108 holds it also in engagement with the ratchet wheel 109. The ratchet wheel 109 has two posts 113 thereon, placed toward the outer periphery of the ratchet. In two places teeth are omitted from the periphery of the ratchet 109, as illustrated at 114.

15 A bell crank lever 116 is mounted pivotally upon the bracket 24 in such a position that one arm 117 may be engaged by the posts 113 on the ratchet wheel 109 to pivot the bell crank 116. An opposite arm 118 of the bell crank 116 passes through an opening in a plate 119 which is mounted directly over the electrical switch 84, with a free end of the plate in contact with the electrical insulation at the top of the switch. The bell crank lever 116 is urged toward the posts 113 by means of a spring 121 and attempts to urge the arm 118 out of the opening in the plate 119. This is possible only when the lever 36 of the code bail 29 is moved downwardly due to the inward movement of the code bail, and exerts pressure on the top of the plate 119, moving it downwardly, and thus freeing the arm 118 from the opening in the plate 119.

30 The cam assembly 49 is formed of six cams 123 to 128, inclusive. Acting as cam followers for the cams 123 to 128 are six electrical switches 131 to 136, inclusive. Each of the electrical switches 131 to 136 is directly connected with an individual electrical switch 92 to 97, previously mentioned. 35 Five of these switches correspond to the five impulses in the standard Baudot code, the sixth switch corresponding to a start-stop impulse, which is usually associated with such code transmission. 40 At certain intervals in the cycle of operation of the shaft 46 the switches are successively closed, which acts as a distributor for the code impulses which are being sent out over an outgoing line 138. In the event that a switch 92 to 97 has not been closed, there will be no impulse 45 at the corresponding electrical switch 131 to 136. This results in a no-current condition on the transmitting line, when the appropriate cam closes that switch, which results in a spacing impulse being transmitted.

50 In describing the operation of the apparatus the description will proceed on the basis that the A key top has been depressed, as the operation of the device is very similar upon the depression of the B or C key tops. The major difference is that there is no timing device affiliated with these latter key tops acting to hold an electrical switch closed for a predetermined time interval to allow the visible signal to indicate to the operator of the transmitting apparatus that a certain key top has been depressed. However, certain locking levers have been provided in its place to insure the signal during a complete cycle of operation of the shaft 46.

65 The operation of the device is as follows:

Upon depression of the A key top, key lever 71 is pivoted inwardly on rod 14, its end 21 engaging the upper end of the lever 26. The lever 26 is thus pivoted about its base, where it is secured in block 33, causing it to move inwardly and also imparting a corresponding movement to the code bail 29, which is an integral part of the lever. The code lugs 34 on the code bail 29 have been prepositioned with the body projection of the first 70 two lugs on the left-hand side of the bail (see Fig. 75

1) above the code bail whereas the remaining three lugs are positioned with their body projections below the code bail. The two lugs positioned with their body projections above the code bail 29 will engage the lugs on the front edge of the code levers 39, whereas the lugs positioned with their body projections below the bail will enter a slot formed in the front edge of the code levers. The two code levers 39 engaged by the code lugs will be forced inwardly against the tension of their springs 41, pivoting about their point of connection in the block 33. The lever 36, of the code bail 29, will exert pressure upon the plate 119, causing the electrical switch 84 to be closed. Upon the closing of the switch 84, an electrical circuit will be established which will energize the magnet 79, and will also establish a circuit to cause the electric light 28 to be illuminated, thus acting as a signal that key top A has been depressed. The energization of the magnet 79 causes the armature 73 to move to the right, as viewed in Fig. 3, thereby releasing the upturned end 72 of the cam follower 65 and allowing the cam follower to move under the tension of its associated spring 70. The cam follower 65 will pivot in a clockwise direction, as viewed in Fig. 3, thereby removing the member 71 from its blocking position with respect to the three pawls 103 of the clutching mechanism. The three pawls will move in a counterclockwise direction (Fig. 6), under the force of their individual springs 105 and cause a tooth on one of the pawls to engage the teeth in the ratchet wheel 101. This, in turn, causes rotation of the shaft 46 through engagement with the constantly-rotating sleeve 51. The contour of the cam 57, which is associated with the cam follower 65 is of such a shape that the cam follower will be depressed immediately after the latter operation described has occurred, and held in a downward position against the tension of the spring 70, so that the armature 73 may again resume a blocking position upon the upturned end 72 of the cam follower 65 when the magnet becomes deenergized and the spring 81 moves the armature 73 to its normal position. The downward movement of the cam follower 65 causes the member 71 to be moved downward also, which positions it to engage the three pawls 103 upon the completion of a cycle of operation of the shaft 46, causing the pawls to be moved outwardly against the influence of their corresponding springs 105 and thus disengage the engaging tooth from the ratchet wheel 101, the shaft 46 no longer being rotated. The roller 74, at the lower end of the bell crank lever 76, will enter the notch in the disk 61 under pressure of its associated spring 77 and thereby positively disengage the tooth of the pawl from the ratchet wheel 101. This, as previously explained, serves as an anti-singing device.

The two selector levers 39, corresponding to the code lugs 34 whose body projections were positioned above the code bail 29, have been forced inwardly, as previously mentioned. Their upturned arm 43 moves inwardly and closes the two corresponding electrical switches 96 and 97. Immediately thereafter the cams 53 and 60 cause the cam followers 64 and 68 to move downwardly, against the tension of their corresponding springs 70, causing the locking bar 44 to move downwardly also and position itself against the rear top edge of the code levers 39, thus holding the code levers in that position. The other three code levers are locked in their normal, outward position. The operator can now release the A key top, but 75

the code levers will be held in their respective positions until a cycle of operation of the shaft 46 has been completed. At the appropriate position of the shaft 46 the cam followers 64 and 68 will be moved downwardly, by means of their springs 70, resulting in the locking bar 44 moving upwardly out of locking engagement with the rear top edge of the code levers, thus allowing the code levers to move to their normal, outward positions if not already there.

Upon the downward movement of the locking bar 44 its lug 98 will come in contact with the insulator on the electrical switch 92 and force it outwardly, thereby breaking the circuit in which the switch 92 is connected. The opening of the switch 92 causes the circuit in which the magnet 79 is connected to be likewise opened and thus breaks any current to the magnet, causing it to stay deenergized. Thus, the magnet 79 will not be energized to cause a second cycle of operation of the shaft 46 until the switch 92 has been restored to its normal closed position.

Upon depression of key top A and the inward movement of its corresponding code bail 29, 25 the lever 83 was also caused to pivot inwardly, positioning its hook to be engaged by the hook on the lever 82 in the event that the lever 82 were moved downwardly. The downward movement of locking bar 44 causes the lever 82, connected thereto, to likewise move downwardly. 30 In the event that the lever 83 is still in its inward position, due to the A key still being held in a depressed position, the hooks on the levers 82 and 83 will engage each other, which will prevent 35 the lever 82 from moving upwardly upon the subsequent upward movement of the locking bar 44 by its associated cam followers 64 and 68. As long 40 as the locking bar 44 is held in its downward position, its lug 98 will hold the electrical switch 92 in its open position, thus breaking the electrical circuit of which it is a member. Therefore, 45 the magnet 79 will not be energized and so no further signals can be transmitted. This feature acts as a non-repeat device so that no matter how long the operator depresses the selected key top only a single signal will be transmitted over the line.

As previously mentioned, the electrical switches 96 and 97 were closed. These, in turn, are directly 50 connected to the electrical switches 135 and 136. Upon the rotation of shaft 46 and of the cam assembly 49, the cam 128 will close its associated switch 131 to act as a start signal, for the code signal to be transmitted over the line conductor 138. The cams 123 and 124 will then, in succession, close their corresponding electrical switches 136 and 135, which results in marking impulses being sent over the line conductor 138. As the electrical switches 96 and 97 were the only ones 60 which were closed by the code levers 39, the remaining three electrical switches, namely, 93, 94, and 95, will not establish any electrical circuit with the electrical switches 132, 133, and 134. Thus, as the cams 125, 126, and 127 close these 65 switches in succession, no marking impulses will be transmitted, but spacing impulses instead. Therefore, as the first two code units were the only ones during which marking impulses were transmitted, the letter "A" will be transmitted 70 over the outgoing line conductor 138. As the cam assembly 49 is a part of the shaft 46, it will stop its rotation when the cycle of operation of the shaft 46 has been completed, as previously described. The B or C signals are 75 achieved in the same manner by a similar opera-

tion to the one just described. Any predetermined code signals can be sent out by merely changing the body projections of the code lugs 34 with respect to the code bails 29, 31, and 32. Upon the depression of the A key top the code bail 29 is moved inwardly, and accordingly its lever 36 is moved downwardly, exerting pressure on the plate 119 to close the electrical switch 84. Upon the downward movement of the plate 119 the end 118 of the bell crank lever 116 is freed from the plate 119 and the bell crank lever is pivoted in a clockwise direction, as viewed in Fig. 4, by means of its spring 121. The bell crank lever 116 will remain in this position until one of the two posts 113, secured to the ratchet wheel 109, engages its upper hooked end 117 and causes the bell crank lever to be pivoted against its spring 121 in such a manner that its lower end 118 will once again be positioned in the opening in the plate 119, allowing the plate 119 to rise, due to its resilience, and thus open the electrical switch 84. As long as the bell crank lever is positioned to hold the switch 84 in its closed position, the corresponding electric light 88 will be illuminated, designating that key top A had previously been depressed. Movement is imparted to the ratchet wheel 109 by means of the two pawls 107 and 111. The pawl 107 is mounted eccentrically upon the sleeve 51, and rotates continuously therewith. Rotation of the eccentrically mounted pawl 107 causes the ratchet wheel 109 to be advanced step-by-step through engagement with the teeth on its periphery. The second pawl 111 is mounted on the rod 112, which extends from its position of securement on the lower end of the code bail 29. Any depression of the A key top, which causes the code bail 29 to be moved inwardly, will cause the pawl 111 to be moved upwardly, which through its engagement with the teeth on the periphery of the ratchet wheel 109 causes a single step to be imparted to the ratchet. This is necessary because of the two spaces 114 on the periphery of the ratchet 109 where teeth are omitted, so made that there will be a pause immediately after the posts 113 have pivoted the bell crank lever 116. The spaces 114, where teeth have been omitted, are so positioned in respect to the posts 113 that the pawl 107 will not reach this portion of the ratchet wheel 109 during the time that the signal is being sent out and the electrical switch 84 is closed. The spring 108 is positioned as to positively insure that the pawls 107 and 111 will be in engagement with the teeth on the ratchet wheel 109.

The operation of the apparatus, upon the depression of the B and C key tops as previously mentioned, is very similar to the above described operation with the exceptions that there are no timing devices connected for operation with these keys.

A second distinction between the operation of the transmitting apparatus upon depression of the B and C key tops and the depression of the A key top resides in a special locking mechanism which holds the bail, once moved inwardly, in this position until the cycle of operation of the shaft 46 has been completed. The cam followers 66 and 67, which are under the control of the cams 58 and 59, have a hooked forwardly extending portion which is associated with the bails 31 and 32. After either the bail corresponding to the B or C key tops has been moved inwardly, and the shaft 46 has started into rotation, the cams 58 and 59 will cause the cam followers 66 and 67

to move downwardly, which results in the hook at the front end of the cam follower hooking over the bail and securing it, thus preventing it from returning it to its outward position in the event that the operator were to immediately release the selected key. Such a locking device has been found necessary as there is no timing device associated with the B and C keys and it is used to insure that the code bails 31 and 32 will remain in their inward position for a certain length of time so that their levers 37 and 38 may be in contact with the electrical switch 86 or 87 for a sufficient period of time for a signal to be given, by means of the lamp bulbs 89 and 90.

Although a specific embodiment of the invention has been shown and described, it will be understood that this is but illustrative and that various modifications may be made therein without departing from the scope and spirit of this invention.

What is claimed is:

1. In a signal transmitter, a plurality of keys, a bail under the control of each of said keys, a plurality of selector levers permutably controlled by said bails in accordance with predetermined signals, a blocking bar to hold said selector levers in their permuted positions, a bail lock forming a portion of said blocking bar, electrical contact means operated by said selector levers, a distributor for controlling the transmission of said predetermined signals in accordance with said electrical contact means, means responsive to the operation of any one of said bails for releasing said distributor for a cycle of operation, and means under the control of said blocking bar operating after said distributor has been released to disable said distributor releasing means until after said selected bail has been released by said bail lock.

2. In a signal transmitter, a plurality of keys, selector means permutably controlled by said keys in accordance with predetermined signals, electrical contact means operated by said selector means, a distributor for controlling the transmission of said predetermined signals in accordance with said electrical contact means, means for releasing said distributor for a cycle of operation upon the selection of one of said keys, and means operating after said distributor has been released for a cycle of operation to prevent said distributor releasing means from operating to release said distributor for another cycle of operation until after said selected key has been released and said distributor has completed its cycle of operation.

CARL W. SWAN.
